ADJUSTABLE CLAMP FLANGE FOR SPRING HINGES AND THE LIKE

Filed Dec. 17, 1928

Inventor:
William J. Keene.

By Fisher Clapp, Somers Pond, Mass.

UNITED STATES PATENT OFFICE

WILLIAM J. KEENE, OF CHICAGO, ILLINOIS, ASSIGNOR TO CHICAGO SPRING HINGE COMPANY, OF CHICAGO, ILLINOIS, A CORPORATION OF ILLINOIS

ADJUSTABLE CLAMP FLANGE FOR SPRING HINGES AND THE LIKE

Application filed December 17, 1928. Serial No. 326,436.

This invention relates to clamp flanges, and more particularly, to adjustable clamp flanges, for hinges, door stops, and the like, such as used on partitions, lavatory partition 5 hanging stiles, and the like, usually of marble or glass. While the device is illustrated as applied to a spring hinge for use on lavatory doors, it may be applied to any other type of hinge or to a door stop, and therefore I do not 10 desire to be limited to such use.

The primary object of the invention is to provide an adjustable clamp flange in which there is provided an adjustable flange or side plate, rigidly but nevertheless adjustably 15 associated with the angular body comprising in part the web or jamb leaf and the other clamp flange or side plate of the hinge or door stop so as to keep the adjustable clamp flange rigid with the web of the hinge at all 20 times and at any and all positions of its adjustment with respect to the web and stationary clamp flange or side plate, irrespec- 25 tive of the thickness of the partition hanging stile or other part to which the device is clamped. Whether applied to a door stop or to a hinge, as illustrated, through the medium of its clamping flanges including the adjustable clamp flange and the other clamp flange, formed with the web or jamb leaf 30 rigid with the barrel of the hinge or other- wise formed as a part of the door stop or clamp of a pivot hinge, the device can be adjusted to fit and be firmly clamped to said stile or other part for all adjustments thereof.

35 A further object of the invention is to pro- vide an adjustable clamp flange for door stops or hinges of the types specified, partic- 40 ularly a lavatory door spring hinge, in which the slidable or adjustable connection between the adjustable clamp flange and the web, in addition to holding said flange at right angles or other suitable or given relation to the web at all times, is located at right angles to the adjustable clamp flange 45 and entirely or wholly without, or exteriorly of, the space between the clamp flanges which accommodates the partition or stile, so that the edge of the partition or stile, especially of marble or the like, and the inner faces of the 50 flanges may be left perfectly flat and smooth

and without projections on their faces, and therefore will snugly fit together and may be firmly clamped without chipping, mortising or cutting of the partition or stile and difficulty in mounting obviated. Furthermore, the exterior surface of the web flange is left flat or perfectly smooth and free from openings, slots, fastenings, or other projections which would mar the surface and appearance thereof and which render adjustable clamp flanges of door stops or hinges, as at present employed, unsightly and objectionable in appearance.

55 With the above and other objects in view, the invention consists in certain novel combinations and arrangement of parts to be hereinafter more particularly set forth.

60 In the accompanying drawings:

Figure 1 is an elevation showing a lavatory door with spring hinges having the novel 70 adjustable clamp flange applied.

Figure 2 is an enlarged fragmentary plan view of a portion of a partition hanging stile and door with the hinge applied by means of the novel adjustable clamp flange.

75 Figure 3 is a front elevation with the hinge barrel broken away and in section.

Figure 4 is a sectional view taken on the line 4-4 of Figure 2.

Figure 5 is a horizontal sectional view 80 taken on the line 5-5 of Figure 3.

Figure 6 is a vertical sectional view taken on the line 6-6 of Figure 4.

Figure 7 is a horizontal sectional view 85 taken on the line 7-7 of Figure 3.

Figure 8 is a perspective view of one of the clamp flanges, the same being the adjustable clamp flange looking from the exterior side.

Figure 9 is a sectional view showing the ad- 90 justable clamp flange applied to a door stop.

Referring to the drawings in detail, in Figure 1 is shown the usual or any preferred form of lavatory structure, including the usual partitions arranged to divide the front 95 structure or stile, and 1 designates the partition hanging stile of marble, glass or the like, in which is hung the door 2 on hinges 3, equipped with the novel adjustable clamp or clamp flange constituting the subject mat-

ter of the present invention. Usually the door is thinner than the stile, but this is not essential.

The hinge is shown comprising a barrel 4 formed with a door plate 5 which may be provided with holes for securing the same in a recess or seat cut in the edge of the door by means of screws in the usual manner, or otherwise, as is common in the art. The barrel has a plug 6 secured in one end thereof—as illustrated, the lower end—by riveting or in any other convenient manner, and a plug 6 turnable in the other or upper end thereof. Each plug has a reduced extension 7 recessed or encircled by the end of the spring 8 if the hinge is of the spring type, the recess or notch indicated at 9 serving to interlock the end of the spring with the plug. The plugs are bored out axially to receive a pin 10 which extends through the barrel 4 in the end member or pivot ears 11, held from displacement by screws 11'. One of the plugs—and in the form shown, the upper plug 6—is provided at intervals therearound with radial holes or seats 12 for a pin 13 which is adapted to engage the edge of the jamb leaf 14, as shown more particularly in Figures 4 and 7. In practice, the plug 6 at the top is turned by means of a suitable tool until the spring is placed under the desired tension, after which the pin 13 is inserted in the proper hole 12 to engage the web or jamb plate 14 at its adjacent edge, door leaf, or other part, and maintain the spring tension which serves to swing the door attached to the door plate 5 to an open or, reversely, to a closed position, as desired, depending on the direction of winding of the spring. Usually, these doors are adapted to normally remain open, but this does not affect the action of the clamp device.

The door leaf or plate 5, as previously stated, is formed with the barrel 4, and the jamb leaf or web 14 straddles the same and is connected to the pivot ears or end members 11 and thereby to the pin 10, as clearly shown in Figure 4 of the drawings. The jamb leaf 14 at one edge is formed with a clamp flange 15 usually disposed at the outside of the hanging stile, and this integral clamp flange is at right angles to the jamb leaf. It may also be pointed out that the jamb leaf or web, except for inside ribs 16 at the top and bottom edges if desired, is made practically flat and smooth, both on the inside and on the outside, and without projections on its faces or openings, slots, fasteners or the like, which would mar the surfaces or detract from the appearance thereof, especially on the outer face which meets the edge of the door and door leaf, thereby avoiding the unsightly and objectionable appearance of hinges as at present constructed. This permits the edge of the stile to snugly

fit the angular plate thus produced to form the web or jamb leaf 14 and clamp the flange 15 without the necessity of chipping, mortising or cutting of the stile, which is a considerable advantage, especially where the stile is of marble or the like.

The opposite or inner edge of the web or jamb leaf 14 is formed with an inward extension or supporting shoulder 17 at right angles thereto, and shown in Figure 7 engaged by the pin 13 in one winding of the spring. The extension 17 is located closely adjacent the barrel 4 and preferably has its outer face arcuate and extending between the end members or webs 18 which serve as connections between the web and the end members or nuts 11 so that the barrel will clear the extension. The extension is shown provided with a plurality, preferably a pair, of openings 19 adapted to slidably and adjustably receive pins or lugs 20 of corresponding number, projecting outwardly at right angles from the outer face of an adjustable clamp flange or side plate 21 which engages the opposite side of the stile. The openings 19 and pins or lugs 20 may be of any suitable shape or cross section, but are preferably round because of facility of manufacture. The clamp flange or side plate 21 is shown with a portion of reduced thickness along one edge and at the outer or exposed face thereof, adjacent the web 14, as indicated at 22, from the face of which reduced portion the pins or projections 20 extend at right angles to the side plate 21 and parallel to the web 14 to engage the openings 19, thereby providing means for holding said flanges rigidly in parallel relation at all times and with the adjustable side plate or clamp flange 21 at right angles to the web 14. The web or jamb leaf 14 and the clamp flange 15 may be considered as a whole in the form of an angular or right-angled clamp flange in which instance, the adjustable clamp flange 21 is maintained rigidly at right angles to the web or jamb plate part of the angular clamp flange, and the connection is located entirely or wholly without and exteriorly of the space between the flanges which receives the stile. The connection referred to is that of the pins or projections 20 with the openings 19 in the extension 17 which is integral with and projects rigidly from the angular clamp flange and specifically the edge of the web or jamb plate adjacent the barrel. By this means, the edge of the partition stile, especially when of marble, and the inner faces of the side plates or flanges may be left perfectly flat so that the fit is snug and unsightly appearance is avoided. In hinges or door stops as heretofore constructed, the connections between the clamp flanges were made with fasteners through the web or jamb leaf or by fasteners or screws at right angles to the web and parallel to the adjustable side plate or clamp 134

flange extending through slots and depending on friction to hold the parts together, and not rigid at all times as with the sliding connection of the present device produced by the pins 20 engaging the openings 19. In previous devices, not only were the adjustable clamp flanges or side plates, corresponding to plate 21, loose and capable of relative angular movement in planes parallel at right angles to the web and not rigid at all times or at any and all positions of its adjustment with respect to the web and stationary clamp flange or side plate, but it was difficult, if not impossible, to rigidly connect the adjustable clamp flange to the web. Moreover, chipping or cutting of the stile was necessary to accommodate the connections, fastenings, or parts of the adjustable clamp flange protruding on the inside of the web, and the exposed face of the web or jamb leaf was marred by openings or fastening means. This is entirely avoided by the present structure, and owing to the pins 20 snugly engaging the openings 19, the clamp flange or plate 21 is maintained in rigid connection with the web through the extension 17, while still permitting necessary adjustment to accommodate the stile and be firmly clamped thereto. The clamping is effected in the usual or any preferred manner, as by means of bolts 23 engaging openings in the stile and clamp flanges in registry, the openings in the clamp flange 21 being designated at 24. However, the projections or pins 20 of the clamp flange 21 extend outwardly and are therefore exterior to the surfaces which engage the stile, but the extension 17 and pins 20 are indiscernible, since they are hidden behind the jamb leaf and the barrel, whether the door is open or closed, and thereby does not detract from the appearance of the hinge. Sufficient adjustment of the clamp flange 21 is allowed by the movement of the pins 20 in the openings 19 to accommodate variations in the stile or partition thickness, and can be applied without re-fitting or extra expense. The reduced edge portion 22 allows for additional clearance and adjustment between the stile or partition and the inner face of the extension 17, and this edge may be further recessed, as indicated at 25, to give additional clearance where the edge of the plate 21 meets the inner face of the jamb leaf. Of course, the hinge is used in the ordinary way, and the tension of the spring may be adjusted to keep the door in an open or closed position.

In Figure 9 of the drawings, the structure is shown applied to a door stop having a channel 26 holding a cushion bumper 27, the other parts being correspondingly numbered.

The structural details herein shown and described may manifestly be more or less varied by persons skilled in the art without departing from the principles of the invention or sacrificing any of its advantages.

Hence, I do not limit the invention to the particular structure illustrated, but reserve all such variations, modifications and mechanical equivalents as fall within the spirit and purview of the claims.

I claim as my invention:

1. In a door fixture of the class described, the combination of a part adapted to engage the door, and an adjustable means for mounting the fixture on a partition or the like, said means including a web adapted to be positioned against the edge of the partition, a pair of normally parallel, oppositely disposed flanges, extending laterally from said web adjacent opposite edges thereof, said flanges being adapted to embrace a portion of said partition, one of said flanges being rigid with said web and the other flange being independent thereof so as to be adjustable towards or from said rigid flange, a bracket part carried by said web, extending laterally therefrom and overlapping a part of said adjustable flange, and means for adjustably connecting said adjustable flange and bracket part comprising a tongue projecting from one of said parts towards the other, the other part being provided with an opening for adjustably receiving said tongue.

2. In a hinge of the class described, the combination of a door leaf, a partition leaf, a hinge barrel integral with one of said leaves, ears formed integral with the other of said leaves and cooperating with said barrel to pivotally connect said door and leaves, a flange extending laterally from said partition leaf adjacent its outer edge and integral therewith, an adjustable flange normally disposed in a plane substantially parallel with the plane of said integral flange and having its inner edge disposed adjacent said partition leaf, a bracket part formed integral with said partition leaf, overlapping a part of said adjustable flange on the outside thereof and provided with an opening, and a tongue projecting laterally outwardly from the outside face of said adjustable flange and fitting adjustably in said bracket opening.

3. In a hinge of the class described, the combination of hinge leaves pivotally connected adjacent their inner edges, and a pair of flanges associated with one of said leaves for embracing a part to which the hinge is to be connected, said flanges being disposed substantially parallel to each other and extending laterally from the leaf, one of said flanges being rigid with said leaf and the other being adjustable towards or from said rigid flange, a bracket part associated with said leaf, extending laterally therefrom and overlapping a part of said adjustable flange, and means for adjustably connecting said adjustable flange and bracket part comprising a tongue projecting from one of said parts towards the other, the other part being pro-

vided with an opening for adjustably receiving said tongue.

4. In a hinge of the class described, the combination of hinge leaves pivotally connected adjacent their inner edges, and a pair of flanges associated with one of said leaves for embracing a part to which the hinge is to be connected, said flanges being disposed substantially parallel to each other and extending laterally from the leaf, one of said flanges being integral with said leaf and the other being independent thereof but adjustably connected thereto, and means for so connecting said flange to said leaf comprising a pair of spaced bracket portions integral with said leaf and extending laterally therefrom into overlapping relation with respect to said adjustable flange and provided with apertures extending therethrough, and a pair of dowel pins extending laterally outwardly from the face of said adjustable flange and slidably fitting in said openings.
